(57) **CLAIM**

The ornamental design for a body composition analyzer with scale, as shown.

DESCRIPTION

FIG. 1 is a perspective view of an embodiment of a body composition analyzer with scale showing our new design; FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a perspective view showing a condition in which the handle is removed thereof;

FIG. 9 is a front elevational view showing a condition in which the handle is removed thereof;

FIG. 10 is a rear elevational view showing a condition in which the handle is removed thereof;

FIG. 11 is a top plan view showing a condition in which the handle is removed thereof;

FIG. 12 is a bottom plan view showing a condition in which the handle is removed thereof;

FIG. 13 is a right side elevational view showing a condition in which the handle is removed thereof; and,

FIG. 14 is a left side elevational view showing a condition in which the handle is removed thereof.
